PEN

Oscar E. Weissenborn, 60 Mountain Road, Verona, N.J.

Filed June 4, 1963, Ser. No. 75,216

Term of patent 14 years

(Cl. D74—17)

*Fig. 1.**Fig. 2.**Fig. 3.*FIG. 1 is an enlarged elevational view of a pen embodying my new design;

FIG. 2 is an enlarged fragmentary portion of the pen barrel of FIG. 1; and

FIG. 3 is a cross section taken along the lines 3—3 of FIG. 2.

The dominant feature of my design resides in the transparent plastic barrel portion which is circular in cross section, having smooth outer sides and embedded therein highly reflective metallic plates which are clearly visible through the barrel.

I claim:

The ornamental design for a pen, substantially as shown and described.
